UNITED STATES PATENT OFFICE

OTTO BAUMGARTNER, OF DURRENAST, NEAR THUN, SWITZERLAND, ASSIGNOR TO
ARNOLD HAEFELI, OF MUNICH, GERMANY

CARBURETOR

Application filed October 23, 1926, Serial No. 143,694, and in Switzerland December 19, 1925.

The present invention refers to carburetors for internal combustion engines of the type in which the amount of air passing through the induction pipe of the motor is regulated by means of a regulating valve arranged transversely to the flow of air. The present invention comprises improved constructions of such carburetors.

According to the present invention the regulating valve controls the flow of air through channels of oblong cross-sections and simultaneously the exit areas of the fuel nozzles so that the throttling curve of the regulating valve, obtained by plotting the uncovered cross-sections as abscissæ and the paths of the valve as ordinates, and the curve of the exit areas of the fuel nozzle, obtained by plotting the uncovered areas of the fuel nozzles as abscissæ and the paths of the valve as ordinates, are straight lines and are in proportion to each other; the exit of the fuel occurring always in the smallest cross-sectional area through which the air passes and the discharge opening of the fuel nozzle being parallel to the fuel level in the chamber containing the float.

Other objects of the invention are improvements to details of this carburetor which will be described hereinafter with reference to the accompanying drawings which show constructional examples of the carburetor according to the present invention and of details thereof. In particular:

Fig. 1 shows the arrangement of a carburetor according to the invention on the suction manifold of a motor,

Figs. 2-7 show a first constructional example of which Fig. 2 is an elevation view, Fig. 3 is a horizontal section along line III-III in Fig. 2,

Fig. 4 is a cross-section along line IV-IV in Fig. 2, through the regulating valve and the fuel nozzle;

Fig. 5 is a vertical longitudinal section along line V-V in Fig. 3, showing the fuel

supply, the fuel chamber with the float and the regulating valve;

Fig. 6 is a vertical longitudinal section along line VI-VI in Fig. 3 showing the fuel chamber, the nozzle and the connection between the two,

Fig. 7 is an elevation view seen against the air outlet end with which the carburetor is connected to the suction manifold of the engine;

Fig. 8 is a longitudinal section through a modified type of fuel nozzle, with which a foaming mixture of fuel and air leaves the slot of the nozzle,

Fig. 9 is a cross-section of the nozzle along line IX-IX in Fig. 8,

Fig. 10 is a cross-section of the nozzle along line X-X in Fig. 8.

Referring now to the first constructional example illustrated in Figs. 2-7 1 designates the casing of the carburetor and 2 is the regulating valve or throttle valve constructed as a hollow piston valve. The air for the charge is admitted through an oblong aperture and channel 3 and the charging mixture flows to the suction manifold A of the motor B, to which the carburetor is fixed by means of a flange 5 as is shown in Fig. 1, through an oblong aperture and channel 4. The air thus flows in a transverse direction to the piston valve 2 as is indicated by the arrows shown in Figs. 3 and 4. The fuel nozzle is formed by a horizontally arranged rod 6 provided with a fine slot 7 communicating with a wider slot 8. The nozzle rod 6 is arranged at a point of the inlet aperture 3 where the highest speed of the drawn-in air is present. The fuel is supplied to the carburetor by the fuel pipe 8 joined to a cover 11 of an extension of the carburetor casing 1 by means of a nipple 9 screwed into the cover and a coupling nut 10 as is best seen in Fig. 5. With the bore of the nipple 9 bores 12 and 13 in the cover 11 are communicating and the latter is controlled by a needle valve 14 fixed on a float 15. The

latter is arranged in the chamber 16 formed by the extension of the carburetor casing 1 and is guided by a pin 17 slidably arranged in a slot of a set pin 18. The cover 11 is fixed to the extension of the casing 1 by means of set screws 19 one of which is shown in Fig. 6. The chamber 16 containing the float 15 is in communication with a slot 20 arranged below the nozzle rod 6 by means of a bore 21 (Fig. 6).

The piston valve 2 is provided with a set screw 23, which glides along the slot 7 of the nozzle 6 and which limits the efficient length of the slot 7 through which fuel is drawn by the stream of air. The adjustment of the piston valve is effected in the known manner from the accelerator by a rod 24 (Fig. 1) and a lever 25, the free end of which is connected to a member 26 the end of which is provided with screw thread 27 cooperating with the end-wall 28 of the piston valve 1. The screw thread 27 serves to adjust the no-load position of the piston valve 2. That is to say, by turning the member 26 more or less in one direction or the other, the end of the screw 27 projects from the end wall 28 of piston 2 to a greater or less extent, whereby the amount of the opening of the slot 3 is increased or diminished when the piston is pushed to its limit in one direction and so determines the extent of opening of the slot 3 when the motor is idling. The screw then abuts against the piston bore end wall.

The nozzle rod 6 is provided with a hexagon head 29 by means of which the rod 6 may be withdrawn and angularly adjusted; a set pin 30 engaging a notch 31 in the rod 6 secures the latter in any adjusted angular position. By the angular adjustment the action of the drawn in air on the slot 7 of the nozzle and thereby the amount of fuel sucked through said slot may be varied.

The single piston valve control the inlet and the outlet openings for the air and simultaneously the exit area of the fuel nozzle. The throttling curve and the curve of the fuel discharge areas are straight lines, which curves are obtained by plotting the uncovered cross-sections through which the air flows and the uncovered operative cross-section of the fuel nozzle respectively as abscissæ and the path of the piston valve as ordinates. The atomized fuel is caused in the cross-section of the air inlet channel in which the highest speed of the air is present. Thereupon the air and the fuel atomized in it pass through the large bore in which the piston valve slides, whereby the speed of the air is reduced and the pressure is increased, then the speed of the charging mixture is increased again when the latter passes through the discharge or outlet aperture of the carburetor.

With such fuel nozzles the danger exists that when the carburetor casing expands by

the influence of the heat transmitted from the motor block the slot of the nozzle is narrowed or completely closed if the longitudinally slotted rod-shaped nozzle is not so constructed that it is adapted to withstand lateral thrusts or is relieved of these thrusts.

These disadvantages are overcome by the fuel nozzle illustrated in Figs. 8-10.

This fuel nozzle consists of a hollow member slotted on the top at 32 and provided with holes 33 at the bottom. The bore of the hollow member may be obtained by drilling holes from both sides of the member which holes do not meet so that a diaphragm 34 is left or the fuel nozzle may consist of a tube in which a diaphragm 34 is inserted. The provision of an upper slot 32 and lower bores 33 has the effect that by the action of the suction pressure fuel is drawn into the hollow interior of the tubular nozzle which mixes in said interior with air entering through that part of the slot 32 from above, which does not serve as discharge area for the fuel. Thereby a foaming mixture of fuel and air is obtained which passes through the operative part of the slot 32.

I claim:

1. In a carburetor, the combination with a casing having two parallel bores and a transverse air slot extending across the bores; of a tubular fuel nozzle in one of the bores, said nozzle having a longitudinal slot in its upper portion presented to the air passing through the air slot and a longitudinal series of holes in the lower portion of the nozzle presented to the liquid fuel, a reciprocable valve in the other bore controlling the supply of air through the air slot and the area of the nozzle slot presented to said air.

2. In a carburetor, the combination with a casing having two parallel bores and a transverse air passage over one bore and extending through the other bore; of a tubular fuel nozzle in one bore having a fuel discharge swept by the air through said passage, means to regulate the area of said passage and the area of said discharge, said nozzle having a longitudinal series of holes at its bottom presented to the liquid fuel, and a partition in said nozzle near one end thereof determining fuel supply during the idling of the engine to which the carburetor is applied.

3. In a carburetor, the combination with a casing having two parallel bores of different sizes, a transverse air passage extending across the casing and passing transversely above the smaller bore and through the larger bore; of a piston in the larger bore controlling both the entrance and the discharge of fuel mixture to and from the larger bore, a nozzle member in the smaller bore having a discharge along the length thereof open to air throughout its length, a fuel slot below the nozzle member communicating with the member, a float chamber in the casing communi-

cating with said slot, and a pin on the piston riding over said discharge and limiting the area of said discharge traversed by the air passing through said passage so as to produce 5 a foaming mixture within the nozzle by air entering the discharge at one side of the pin while the fuel discharges at the opposite side.

In testimony whereof, I have signed my name to this specification.
